GEOCHEMICAL SURVEYING

Edwin E. Reper, Tulsa, Okla., assignor to Stanolind Oil and Gas Company, Tulsa, Okla., a corporation of Delaware

Application February 13, 1941, Serial No. 378,785

5 Claims. (Cl. 202—205)

This application pertains to the art of geochemical surveying. As this term is now used it refers to the detection of minute amounts of hydrocarbons at or near the surface of the earth which have migrated upwards from subterranean accumulations of oil or gas and which accordingly, by their relative abundance or rarity, serve as indicators of the presence of such subterranean accumulations.

Numerous investigators have worked with varying success in the last few years at the problem of determining the presence of subterranean petroleum accumulations by direct methods rather than by geophysical or geological investigation. The main hypothesis involved is that these hydrocarbon deposits have been under great pressure for a long period of time at a relatively elevated temperature and that they are made up of constituents some of which are relatively highly volatile. It has been postulated, therefore, that lighter hydrocarbons from the deposit have through the time since the accumulation of the petroleum slowly migrated upward through the strata lying above the pool, eventually to be dissipated into the atmosphere. Obviously the quantities which have thus migrated are of an extremely minute amount due to the relatively low permeability of the earth, among other factors. Thus at or near the surface of the earth the soil atmosphere or soil air should contain a very small quantity of some of the lighter petroleum hydrocarbons if there is an oil or gas pool below. Since the soil itself is to a certain extent a sorbent, some of the hydrocarbons which have migrated to this point are sorbed on the surface of the fine grains of earth. This quantity will be dependent upon numerous factors including the partial pressures of the hydrocarbons in the soil gas, their molecular weights, the sorptive capacity of the soil, the temperature of the soil particles, etc.

Investigators have attempted to determine by various analytical procedures the presence or absence of hydrocarbons in the soil air or sorbed on the surface of soil samples in order to determine the presence of the underground reservoirs. It was discovered that the presence of methane in the soil air or sorbed on the soil itself was of relatively negligible value as an indicator because methane is not only a constituent of petroleum but is also a product of decomposition of vegetable matter and hence is found in considerable amounts wherever there is decaying vegetable matter. Studies on the presence of the higher paraffinic hydrocarbons, ethane, pro-

pane, etc., offered more theoretical advantage because such materials are apparently not evolved in normal surface animal or plant life. On the other hand, these substances are of much lower concentrations so that exceedingly sensitive micro-analytical equipment is necessary to determine the relative amounts of these constituents present in the sample.

The two main methods of gathering a sample have been mentioned above. One may either dig a hole into the ground and obtain from the hole a sample of soil air, or he may remove under suitable conditions a sample of the subsoil and treat it so that the hydrocarbons are desorbed and can be gathered for analysis. The former system is the older and apparently simpler technique but investigators early determined that there were many inherent disadvantages such as the length of time involved in preparing the hole and gathering the sample, the contamination from the atmosphere, and the low permeability of the soils in some areas making it extremely difficult to withdraw the gas sample from this type of soil. Emphasis in sampling has shifted to the taking of soil samples which are subsequently desorbed of their hydrocarbons.

In collecting subsurface samples by this method a suitable amount of soil is collected from a point, usually several feet or more below the surface of the earth and is removed in a sealed container to the laboratory. Here the customary procedure has been to draw off the sorbed hydrocarbons by heating the sample. The sorbed hydrocarbons are presumably held in a very thin, approximately monomolecular layer on the soil particles with such force that it is necessary, utilizing this prior art technique, to heat the samples to a rather high temperature of the order of several hundred degrees centigrade in order that the hydrocarbons may be disengaged or desorbed from the soil samples so that they may be collected.

I have discovered that there are extremely serious consequences which can result from this degree of heating of the samples. One outstanding difficulty lies in the fact that there are present in the soil not only various minerals and the sorbed hydrocarbons, but also other substances which I believe to be largely vegetable in nature, which decompose when heated, giving off in the process large volumes of gases which for convenience I will refer to as pseudo-hydrocarbons. The presence of these pseudo-hydrocarbons in the microanalytical apparatus is highly undesirable and may very easily lead to a spurious re-

sult. A second and even more undesirable effect of the strong heating lies in the fact that any higher hydrocarbons which have been sorbed in the sample such as eicosane, pentacosane, triacontane, and the like, have a tendency to decompose at these temperatures and to break up or crack into lighter hydrocarbons. Obviously, in so doing they will produce a greater volume of these lighter hydrocarbons which will be measured and reported as a higher concentration than was actually present. It is obvious from the above that it is desirable to remove the hydrocarbons without heating them sufficiently to cause appreciable decomposition or the formation of pseudo-hydrocarbons.

Thus while prior art soil desorption techniques are restricted largely to the recovery of hydrocarbons having up to about eight carbon atoms per molecule, it is possible in accordance with my invention to recover those containing from ten up to thirty or more carbon atoms per molecule as well as lighter hydrocarbons.

It is an object of my invention to provide a method and apparatus for desorbing soil samples of their sorbed hydrocarbon content without excessive heating and thermal decomposition produced thereby.

It is a further object of my invention to provide a method and apparatus for desorbing soil samples to recover therefrom heavy sorbed hydrocarbons, such as those containing from ten to thirty carbon atoms, and other heavy molecules without decomposing the same.

It is a further object of this invention to provide a microanalytical method and apparatus for the gathering and selective analysis of sorbed hydrocarbons from soil samples.

Further object and advantages of my invention will be understood upon reading this specification.

In one of its broad aspects my invention contemplates desorbing soil samples and recovering hydrocarbons and other components under conditions giving a long mean free molecular path, or, in other words, in a molecular still.

The accompanying drawings illustrate certain embodiments of my invention. These form a part of this specification and are to be read in conjunction therewith. In these drawings, the same numeral indicates the same or corresponding parts in all figures.

Figure 1 is a diagrammatic elevation, partly in section, of one type of apparatus for desorbing soil samples of their sorbed hydrocarbon content without thermal decomposition, in accordance with my invention.

Figures 2, 3 and 4 are diagrammatic elevations of a portion of the apparatus of Figure 1 together with other equipment useful in the transfer of desorbed soil hydrocarbons from the apparatus shown in Figure 1 to an analytical apparatus.

Figure 5 is a detailed cross-section taken along the line 5-5 of Figure 4.

In Figure 1 a sample of soil 11 is placed in the bottom part of a flask 12. This flask is furnished with two tubes 13 and 14 and at the top terminates in a standard ground joint 15. A corresponding ground joint on receiver 16 makes a very tight connection with joint 15, so that with the use of a very small amount of high vacuum grease it is possible to make an air tight seal at this point. Receiver 16 is hollow and elongated, the lower portion of it extending within a few centimeters of the soil sample in flask 12. 75

Receiver 16 may be filled with a liquid from the top.

Tube 14 is connected through an off-on stop cock 17 to lines 18 and 19. Line 19 is connected through an off-on stop cock 20 with line 21 which in turn through off-on stop cock 22 and line 23 connects with a source of hydrocarbon-free nitrogen 24. Line 18 passes into a trap 25 which can be refrigerated, then into a second trap 26, which also can be refrigerated. An off-on stop cock 27 connects trap 26 to a line 28 which communicates directly with a mechanical vacuum pump 29, such as a Hyvac pump, capable of producing a vacuum of the order of 1 micron of mercury.

Line 30 communicates with line 18. It is connected through off-on stop cock 31 to line 32 and rubber tubing 33 which in turn connects with line 34 which passes through a two hole rubber stopper into the top of flask 35. Another tube 36 extends through the stopper nearly to the bottom of the flask 35. It is connected through a rubber tube to an overflow so that the contents of this line may be emptied into a graduate 37. A pinch clamp 38 is used in conjunction with rubber tubing 33 to seal off one opening to the flask. A pinch clamp 39 is similarly used to seal off the second opening into flask 35.

Tube 43 is connected by means of off-on stop cock 40 with lines 41 and 42. Line 42 is connected through off-on stop cock 43 and line 44 with stop cock 22 and the nitrogen container 24. Line 41 is bent to form a trap 45 which may be refrigerated. This is connected to lines 46 and 47.

Line 47 communicates through an off-on stop cock 48 and line 49, rubber tube and pinch clamp assembly 50 and line 41 with a flask 52, this whole assembly being identical with that from line 30 to flask 35. Line 53, similar to line 36, leads through a rubber tube and pinch clamp assembly 54 so that the end of this line can empty into a graduate 55. Graduates 55 and 31 are approximately of the same volumetric capacity as their corresponding flasks 52 and 35.

Line 46 communicates through off-on stop cock 56 and line 57 with a high vacuum pump 58 such as a Langmuir pump. This in turn is connected through line 59 with the mechanical vacuum pump 29.

The operation of the apparatus to desorb the soil of its hydrocarbons and other volatile components is as follows:

Receiver 16 is removed from flask 12. A weighed quantity of soil sample is placed in flask 12. Stop cocks 17 and 40 are closed. The upper part of ground joint 15 is lubricated with a very low vapor pressure vacuum stop cock grease, such as Apiezon "N" grease, and receiver 16 is replaced in flask 12, sealing joint 15. It is, of course, possible to use a mercury seal between the receiver 16 and flask 12 if it is discovered that vapor from the grease is contaminating the sample but this should never be the case if the joints are properly constructed.

Stop cocks 20, 22, 31, 40, 43, and 48 are closed at the start of the run. Trap 25 is surrounded with a bath of subliming carbon dioxide in a suitable container and similarly trap 26 is surrounded by a bath of liquid air. Stop cock 17 is opened and pump 29 is started up. This will evacuate flask 12 and the lines from this flask to the pump to an ultimate pressure of less than a millimeter of mercury. Most of the soil air originally in the sample, nearly all of the water present, and a very small amount of the adsorbed soil hy-

drocarbons are removed from the sample by this procedure. The water vapor and other materials condensable at -78°C . will be condensed in trap 25 while gases which are condensable between -78°C . and about -188°C . will be condensed in trap 26. Oxygen, nitrogen, methane, and other substances which are non-condensable at approximately -188°C . in the respective proportions present will be pumped off from the system. During the latter part of this evacuation, flask 12 is surrounded with a bath which 12a which can be of any suitable liquid such as water or oil, and this is heated to the order of 40 to 50°C . The soil 11 in flask 12 has by now been swept fairly clean of the materials that are not desired in making the test, i. e. the gases which are not sorbed on the soil sample, water, etc. On the other hand, the sample has not been heated sufficiently to cause an appreciable amount of thermal decomposition. After this evacuation. After this evacuation which should take of the order of 5 to 30 minutes at around 40 to 50°C ., stop cock 17 is closed off and stop cock 40 is opened. Trap 45 is surrounded with a liquid air bath and liquid air is poured into receiver 16. The temperature of the bath surrounding flask 12 is increased, and the high vacuum pump 58 is placed in operation to evacuate flask 12 and the attendant system to a final vacuum of the order of 0.5 micron of mercury or lower, preferably from about 0.1 to about 0.01 micron. The maximum pressure is such that the mean free path of the molecules to be recovered is about as great or greater than the distance from the upper surface of the soil sample to the bottom of the refrigerated surface of receiver 16.

The temperature to which the bath surrounding flask 12 is raised is sufficiently low so that no appreciable decomposition of soil constituents occurs. For the average soil a temperature of the order of 100°C . is appropriate. Other temperatures such as 75°C . to 150°C . can be used.

While this evacuation is taking place, the gases which have condensed in traps 25 and 26 can be removed and analyzed for the hydrocarbons present. Flask 35 is removed, filled with water and replaced, and the pinch clamps 38 and 39 are opened. Stop cock 27 is now closed and the refrigerants from traps 25 and 26 are removed permitting these traps to warm to room temperature. Hydrocarbon-free nitrogen from the supply under pressure in container 24 is now swept through the system by opening stop cocks 22, 20 and 31 to permit nitrogen slowly to flow through the system, displacing the water in flask 35 which flows out through line 36 into graduate 37. This nitrogen will sweep the gases previously condensed in traps 25 and 26 into flask 35. The nitrogen is allowed to flow through this system until a suitable amount has collected in flask 35, which is measured by the amount of water displaced into the graduate 37. Stop cocks 20 and 22 are then closed.

I have found that one liter of gas is a convenient amount but other volumes can be used if desired. By this system all of the condensables from traps 25 and 26 are collected in the flask 35. Pinch clamps 38 and 39 are now closed and the rubber tube is disconnected from line 32. The flask containing the nitrogen and condensables can now be removed and the contents displaced into a suitable micro gas analysis apparatus for measurements of the hydrocarbons. The type of gas analysis apparatus used for this purpose does not form part of my invention. One example of

5 a suitable apparatus is disclosed in United States Patent 2,212,681 issued in the name of T. H. Dunn.

During this time the soil sample has been subjected to a very high vacuum at a moderate temperature, with a surface at liquid air temperature only a short distance away. Nearly all the molecules present in the space above the soil in flask 12 will therefore be removed. Those which are condensable at liquid air temperature will condense either on the surface of receiver 16 or if the material has an appreciable vapor pressure at this temperature, some of its molecules will find their way into trap 45 and will be condensed there. The thermal energy of the hydrocarbons sorbed on the soil sample at the temperature of around 100°C ., combined with the long mean free path of the molecules in the space over the soil, will be sufficient under this condition to drive these hydrocarbons off from the soil sample so that they will be collected mainly on the refrigerated receiver 16. Since the temperature of the bath surrounding flask 12 is too low to cause appreciable thermal decomposition of the vegetable matter present, there will be only a negligible amount of pseudo-hydrocarbons formed and thereafter condensed on the outside of receiver 16. On the other hand, the molecules of the heavier hydrocarbons present will not be cracked at the temperature involved and will condense on the refrigerated surface of receiver 16 in their true quantities. Finally, it should be noted that there is no opportunity for contamination of the material condensed on receiver 16 from the material used in pump 58 (preferably mercury) since any molecules of this substance will be condensed out on the surface of trap 45. After the flask 12 has been subjected to the highest vacuum possible for some time, preferably of the order of 20 to 100 minutes, stop cocks 40 and 56 are closed. The desorption is by now practically complete. The material condensed in trap 45 can now be analyzed for the presence of hydrocarbons by collecting this material in flask 52. The same procedure is used as was already employed for collecting the materials from traps 25 and 26. Stop cock 40 is closed. The refrigerant is removed from the trap 45 and it is allowed to warm to room temperature. Flask 52 is filled with water. It is then reconnected to line 51. Pinch clamps 50 and 54 are opened. Nitrogen from container 24 is swept through the trap by opening stop cocks 22, 43 and 48 so that nitrogen slowly flows through the system displacing a measured amount of water from flask 52 into graduate 55. These stop cocks are then closed, as are pinch clamps 50 and 54 and the flask 52 containing nitrogen and the volatile constituents from trap 45 can be removed from line 51 and connected to the micro gas analysis apparatus for measurement.

60 The main body of the hydrocarbons desorbed from a soil sample have been condensed on the outer surface of receiver 16 and have not been analyzed as yet. There are numerous methods available for removing receiver 16 from this apparatus and connecting it to a micro gas analysis apparatus for analysis of the constituents. Thus receiver 16 can be removed and inserted into any type of analytical apparatus.

65 One system for removing receiver 16 and analyzing the hydrocarbons condensed thereon will now be described. Nitrogen from container 24 is slowly admitted into flask 12 by opening stop cocks 22, 43, and 48 until the pressure in flask 12 is approximately atmospheric. The ground joint 15 is then loosened by turning receiver 16 and it

is then removed from the apparatus. This removal is accomplished by the apparatus shown in Figures 2, 3, and 4. Essentially this consists of a container by means of which the refrigerated receiver 16 can be removed in an atmosphere of hydrocarbon-free nitrogen until the receiver is placed in an apparatus, wherein the hydrocarbons condensed on the outer surface of the receiver are removed. The container 60 is an elongated hollow cylinder with an opening in the lower end large enough so that the receiver 16 can be pulled up through this opening. The top of the receiver is closed. Through this top there protrudes a rod 61 fitting loosely in a bearing 62. This rod 61 is fitted with tongs 63 which can be lowered over the end of the receiver 16 to clamp over the constriction near the top of the receiver. A small tube 64 leads into the upper part of the container 60 and is attached through a flexible line 65 to a source of hydrocarbon-free nitrogen at a pressure above atmospheric. At the bottom of the container there is a disc 66 pivoted near the opening in the bottom of container 60 so that this disc can be rotated to shut off the bottom of the container.

When the container 60 has been placed over receiver 16 the tongs 63 are engaged and a slow stream of nitrogen is passed in through tube 64, filling the container with an atmosphere of nitrogen. The receiver 16 is then rapidly pulled up into the container by means of the knob at the upper end of the rod 61 and the disc 66 is swung into place shutting off the bottom of the container. The atmosphere inside the container is at a pressure slightly greater than atmospheric so that nitrogen leaks from the container and no air, which might contain stray hydrocarbon vapors, can contaminate the hydrocarbons condensed on the wall of the receiver 16. The container in closed position is shown in Figure 3.

The receiver 16 is removed in this container to an apparatus in which the hydrocarbons can be withdrawn from the cold surface of the receiver without contamination. One such apparatus is shown in Figure 4. The chief member of the apparatus is a vessel 67, the top of which is formed with a ground joint exactly similar to joint 15. The lower part of this vessel is constricted into a tube 68. Before removing condensed substances from receiver 16, a flask 69 is connected to tube 68 by means of a non-lubricated ground joint 70. Near the upper end of vessel 67 there is a side tube 71 which communicates with a funnel or thistle tube 72. Side tube 71 is bent to form trap 73 and terminates in a nozzle 74 which can suitably be directed tangentially to the cylindrical surface of receiver 16 as shown in Figure 5.

A hydrocarbon solvent, the refractive index of which has been very carefully measured with a precision refractometer, is poured into thistle tube 72 until there is sufficient liquid in trap 73 to seal tube 71. Receiver 16 is placed over this apparatus, preferably preflushed with hydrocarbon-free nitrogen, disc 66 is swung out of the way and rod 61 is lowered until the ground joint on receiver 16 is seated in the ground joint of vessel 67. The hydrocarbons on the surface of receiver 16 are now no longer in danger of contamination from hydrocarbons in the air, so the nitrogen supply is cut off from line 65, the tongs 63 are opened, and container 60 is removed. The liquid air in receiver 16 is now removed and the receiver permitted to warm. A standardized quantity of the hydrocarbon sol-

vent, for instance 25 ml., is slowly poured into thistle tube 72, by means of which the material on the surface of receiver 16 is rinsed into flask 69. Receiver 16 can be rotated during this operation, if desired, to increase the effectiveness of the rinse. The flask 69 containing the dissolved material from receiver 16 is now removed from vessel 67. The solvent in which the soil hydrocarbons are dissolved is now analyzed for the presence of these hydrocarbons. One excellent method of accomplishing this result has been described in United States Patent 2,213,905 issued in the name of Joseph B. Clark. It is shown in that patent that the refractive index of the solvent varies with the amount and type of soil hydrocarbons dissolved in it and hence by suitable measurement of the refractive index of the solvent before and after dissolving the hydrocarbons in it, one can obtain a measurement of the quantity of hydrocarbons present. Alternatively a differential refractometer can be employed to measure the change in refractive index of the hydrocarbon solvent occasioned by the rinsing operation.

Suitable solvents for use in this type of measurement include carbon disulfide, benzene, cyclohexane, pentane, etc. I prefer to use, in general, solvents having a higher refractive index than that of the hydrocarbons present, such as carbon disulfide, but solvents of lower refractive index can be used. In order to avoid errors in the analysis due to the presence of water on the surface of receiver 16, which has been removed from the soil sample, I prefer to saturate the hydrocarbon solvent with water before commencing operations. The refractive index of the water saturated solvent is measured, the solvent is then used to rinse the surface of receiver 16 and another measurement of the refractive index is then made. Of course, it is possible to use anhydrous solvent and pass the material collected in flask 69 through a dehydrating agent before the final measurement as an alternative means of eliminating the effect of water collected with the other material condensed on receiver 16.

This method of removing the hydrocarbons condensed on the walls of receiver 16 is but one of several alternative methods. Other methods will suggest themselves to those skilled in the art. Neither is it imperative to use the refractive index method of analysis for the condensed material, since other known methods of analysis can be used.

Another method of analysis which is to be preferred where very accurate separation of the various hydrocarbons removed from the soil by the above desorbing method is desired, is to allow the hydrocarbons from receiver 16 which have been freed from the surface by warming it, to pass into a mass spectrograph. It is well known that very small amounts of various substances can be determined by use of such an instrument. This is described, for example, in an article by H. Hoover, Jr., and H. W. Washburn entitled "A preliminary report on the application of the mass spectrograph to problems in the petroleum industry," published in Petroleum Technology, May 1940, page 13.

While I have described my invention in connection with a preferred embodiment thereof, it will be understood that this is by way of illustration and not by way of limitation and that I do not mean to be restricted thereto but only to the scope of the appended claims. In per-

ticular, while I have shown one form of molecular still in connection with my invention, it will be apparent that various other types of molecular stills can be used.

I claim:

1. Apparatus for geochemical surveying comprising a molecular still for desorbing hydrocarbons from a soil sample, at least one trap connected to said molecular still for trapping hydrocarbons desorbed from said soil sample, means connected with said molecular still and with said trap for evacuating said molecular still and said trap, a sample reservoir for light hydrocarbons, said sample reservoir being connected with said trap, means for passing a hydrocarbon-free gas through said trap and into said reservoir to transfer hydrocarbons from said trap to said reservoir, an additional trap alternatively connected with said molecular still, means connected with said additional trap and with said molecular still for further evacuating said molecular still and similarly evacuating said additional trap, a second sample reservoir for heavy hydrocarbons, and means connected with said additional trap and with said second sample reservoir for passing a hydrocarbon-free gas through said additional trap and into said second sample reservoir.

2. Apparatus for geochemical surveying comprising a molecular still for desorbing hydrocarbons from a soil sample, at least one trap connected to said molecular still for trapping hydrocarbons desorbed from said soil sample, means connected with said molecular still and with said trap for evacuating said molecular still and said trap, a sample reservoir for light hydrocarbons, said sample reservoir being connected with said trap, and means for passing a hydrocarbon-free gas through said trap and into said reservoir to transfer hydrocarbons from said trap to said reservoir.

3. Apparatus for geochemical surveying comprising a molecular still for desorbing hydrocarbons from a soil sample, said molecular still including means having a refrigerated surface for collecting heavy hydrocarbons desorbed from said soil sample, at least one trap connected to said molecular still for trapping light hydrocarbons

desorbed from said soil sample, means connected with said molecular still and with said trap for evacuating said molecular still and said trap, a sample reservoir for light hydrocarbons, said

sample reservoir being connected with said trap and means for passing a hydrocarbon-free gas through said trap and into said reservoir to transfer said light hydrocarbons from said trap to said reservoir.

4. Apparatus for geochemical surveying comprising a molecular still for desorbing hydrocarbons from said soil sample, said molecular still including means having a refrigerated surface for collecting hydrocarbons desorbed from said soil

sample, said means being removable from said still, at least one trap connected to said molecular still for trapping hydrocarbons desorbed from said soil sample which are not collected on said refrigerated surface, means connected with said

molecular still and with said trap for evacuating said molecular still and said trap, a sample reservoir for hydrocarbons, said sample reservoir being connected with said trap, and means for passing a hydrocarbon-free gas through said trap and into said reservoir to transfer said hydrocarbons from said trap to said reservoir.

5. Apparatus for geochemical surveying comprising a molecular still for desorbing hydrocarbons from a soil sample, said molecular still including means having a refrigerated surface for collecting heavy hydrocarbons desorbed from said soil sample, said means being removable from said still, at least one trap connected to said molecular still for trapping light hydrocarbons

desorbed from said soil sample, means connected with said molecular still and with said trap for evacuating said trap and said molecular still to a pressure such that the mean free path of the molecules being desorbed is at least as great as

the distance from said refrigerated surface to the soil sample, a sample reservoir for light hydrocarbons, said sample reservoir being connected with said trap and means for passing a hydrocarbon-free gas through said trap and into said reservoir to transfer said light hydrocarbons from said trap to said reservoir.

EDWIN E. ROPER.
